UNITED STATES PATENT OFFICE.

HENRY JOHN GROSS, OF CHICAGO, ILLINOIS.

DESIGN FOR AN ANDIRON.

Application filed April 15, 1929. Serial No. 30,911. Term of patent $3\frac{1}{2}$ years.

To all whom it may concern:

Be it known that I, HENRY JOHN Gross, a citizen of the United States, residing at Chicago, county of Cook, and State of Illinois, have invented a new, original, and ornamental Design for Andirons, of which the following is a specification, reference being had to the accompanying drawing, forming a part thereof, wherein—

Fig. 1 of the drawing is a front elevation

of an andiron embodying my new design, a removable plaque being shown in dotted lines; and

Fig. 2 is a side elevation thereof, showing the wood supporting portion of the andiron in dotted lines.

I claim:

The ornamental design for an andiron as shown and described.

HENRY JOHN GROSS.
